CLAIM

The ornamental design for a lock for holding power cord to extension cord, as shown and described.

DESCRIPTION

FIG. 1 is a front, top and side perspective view of the lock for holding power cord to extension cord showing my new design;

FIG. 2 is a front elevational view thereof;

FIG. 3 is a rear elevational view thereof;

FIG. 4 is a top plan view thereof, the bottom being a mirror image of the top shown in FIG. 4; and,

FIG. 5 is an end elevational view thereof, the end opposite being a mirror image of the end shown in FIG. 5.

FIG.1.

FIG. 3.

FIG. 2.

FIG. 4.

FIG. 5
